UNITED STATES PATENT OFFICE

WALTER S. EDGE, OF PITTSBURGH, PENNSYLVANIA

DEVICE FOR THE INSTALLATION OF STEEL REINFORCEMENT IN CONCRETE
PAVEMENTS

Application filed December 12, 1928. Serial No. 325,532.

My invention relates particularly to the accurate and economical installation of steel reinforcement of the so-called sheet or mat type in concrete and is particularly adapted to 5 work where a power driven self propelling concrete mixer is employed.

I am quite familiar with the methods now in common use for the installation of electrically welded wire mesh and barmat reinforcement and believe that all of them are 10 open to objections of one kind or another, mainly on account of the labor required for their operation. One method which had a limited use for about seven years employs 15 what is technically known as a "sled" which consists of several pipes or T irons with the stems turned up, laid parallel on the sub-grade and connected together at their forward ends with a yoke which in turn is connected to the concrete mixer by chains or cables. The method of operating the device 20 is as follows:

The sheet of mesh reinforcement is laid across the parallel T irons which support it 25 in its correct position. The concrete is then deposited and worked through the reinforcement and then the supporting sled is drawn forward by the concrete mixer and the process is repeated. This method has the advantages that the cost is small, the placement 30 is accurate, and the labor cost very low, but it has the disadvantage that the stems of the T irons will either leave an actual void in the concrete or create a plane of weakness 35 which is just as bad. For this reason, it has been prohibited by most State highway departments who formerly allowed its use. In order to retain its advantages and eliminate its vital weakness, I have developed the apparatus 40 hereinafter described.

The action of the T irons or pipes (of the old device) as they remain in the concrete is, of course, to create a void extending longitudinally but as they are drawn forward by 45 the concrete mixer they exert an action very similar to that of a finishing machine working on the surface in that they tend to compact and consolidate the concrete on either side, thus tending to retain the void already 50 created. The subsequent action of the finish-

ing machine is not sufficient to destroy the structure thus created. In my invention I retain the feature of practically continuous support for the reinforcement and the feature of having the support withdrawn by the 55 mixer or other power, but eliminate the possibility of creating voids when the supports are moved ahead.

In order that my invention may be more easily described, reference will be had to the 60 accompanying drawings.

Figure 1 is a plan drawing showing a short section of a roadway with the assembled device lying on the subgrade ready for the placement of the steel reinforcement upon 65 it and the depositing of the concrete, part of the top of the connecting member being cut away to show connections.

Figure 2 is a partial elevation and section 70 of the same assembly.

Figures 3 and 3^a are side and end elevational views respectively of one of the reinforcement supporting bars of Figs. 1 and 2.

Figures 4, 4^a and 4^b are side elevational, 75 plan and end elevational views showing a modification of the structure of Figs. 3 and 3^a.

Figures 5 and 5^a are side and end elevational views showing another modification.

Figures 6, 6^a and 6^b are side elevational, 80 plan and end elevational views respectively of another modification.

Figure 7 shows still another modification.

Figure 8 shows the details of a skeleton support and brings out the manner in which the vertical and inclined members should be 85 sharpened and stream lined to reduce the resistance to moving the device and to eliminate the tendency of the support to create a void in the concrete as it is withdrawn, and Fig. 9 is a view taken on the line IX—IX of 90 Fig. 8.

It will be seen from these drawings that the device consists of several parallel members 95 2, which rest on the subgrade and which are connected at their forward ends to a common cross piece or yoke 3, to which are fastened chains or cables 4, 4 which are in turn connected to the concrete mixer or other power. By reference to Figure 6, which shows an elevation of one longitudinal mem- 100

ber of the device to a larger scale, it will be seen to consist of a flat metal plate 6, to which are attached skeleton supports 7, 7, 7 shaped like an inverted sled runner and which are curved down at their forward ends so as to avoid all possibility of fouling the reenforcement. The front and back edges of the vertical and inclined members are ground off to present sharp faces entering and leaving the concrete, see Fig. 8. A glance at Figures 4 and 6 will show that these supports are staggered in plan so that there are no continuous lines of support in any one vertical plane to cause a void or weakened plane when it moves forward. This device was developed to be used primarily on highway work, but it may find other applications when sufficient power is present for its operation. The operation of the device will now be explained.

Referring to Figure 1, we see the installing device resting on the subgrade between the road forms 1—1, the grade having been previously trimmed to the exact cross section required. The chains 4, 4 are connected one to either side of the tractor of the concrete mixer. A sheet of mesh reenforcement is now laid on top of the installer with its edges at the correct distance from the forms, and concrete is deposited on top of it first at the end farthest away from the mixer and continuing this process until the entire section is finished. The mixer then moves ahead, drawing the installer with it and the process is continued. It is not necessary to make the installer as long as the sheet of reenforcement which is being handled because the sheet can extend up onto the chains, for as the device moves ahead it will lift the sheet of mesh up and hold it at the proper height in the zone where concrete is being deposited.

The spacing between the main supporting members 2, Figure 1, will vary with the transverse stiffness of the reenforcement. For a mesh composed of $\frac{3}{8}$ round elements, it may be as much as three feet and for lighter wire mesh it may have to be reduced to half that.

The arrangement of the individual supports 5, 7 and 8 on the base 6 will also vary depending upon the type of reenforcement to be used, but in general it will be advisable to use as few supports as possible and space them as far apart as will give sufficient support, thereby reducing the disturbance created in the concrete when the installer is withdrawn and the load on the mixer necessary to move it.

It will be understood that the invention may be variously modified and embodied within the scope of the subjoined claims.

I claim as my invention:—

1. In a device for the installation of steel reenforcement in concrete structures, a supporting member consisting of a base to which are attached two or more supports with their

long axes paralleling the base and their tops in approximately the same horizontal plane.

2. As stated in claim 1: said supports being set in staggered relationship in plan.

3. As stated in claim 1: said supports having their front and rear edges sharpened.

4. In a device for the installation of steel reenforcement in concrete structures, a supporting member consisting of a base to which are attached one or more skeleton supports with their long axes paralleling that of the base and their tops in the same horizontal plane.

5. In a device for the installation of steel reenforcement in concrete structures, a supporting member consisting of a base to which are attached one or more skeleton supports having the front and rear edges of their vertical and inclined members sharpened, with their long axes paralleling that of the base and their tops in the same horizontal plane.

6. In a device for the installation of steel reenforcement in concrete structures, a supporting member consisting of a base to which are attached two or more skeleton supports having the front and rear edges of their vertical and inclined members sharpened with their long axes paralleling that of the base and their tops in the same horizontal plane each skeleton support being set in staggered relationship with the one preceding it.

7. In a device for the installation of steel reenforcement in concrete structures, a supporting member consisting of a base to which are attached one or more skeleton supports having their long axes paralleling that of the base.

8. A device for the installation of reenforcement in concrete structures, comprising a supporting member adapted to rest upon the surface on which the concrete is to be placed, the upper portion of said device being of skeleton form and the device being of such shape that it is movable in plastic concrete in a direction parallel to its longitudinal axis.
